E. R. PROBERT.
METALLIC WINDOW SASH.
APPLICATION FILED JULY 14, 1903.

973,384.

Patented Oct. 18, 1910.

UNITED STATES PATENT OFFICE.

EDWIN R. PROBERT, OF NORWOOD, OHIO.

METALLIC WINDOW-SASH.

973,384.

Specification of Letters Patent. Patented Oct. 18, 1910.

Application filed July 14, 1909. Serial No. 507,469.

To all whom it may concern:

Be it known that I, EDWIN R. PROBERT, a citizen of the United States of America, and a resident of Norwood, in the county of 5 Hamilton and State of Ohio, have invented a certain new and useful Improvement in Metallic Window-Sashes, of which the following is a specification.

This invention relates to metallic window-sashes and especially to that class having hollow frames and adapted to fire and weather proof conditions.

The principal object of the invention is to produce a hollow frame having grooves 15 formed therein for the reception of the edges of the glass-panes, such grooves being of equal depth at top and bottom edges of the glass-panes and, also, of equal depth at the opposite side-edges of the glass-panes, but such depths of grooves are especially adapted to be readily converted into and maintained at a shallower depth at either top or bottom or at both edges of the glass-panes 20 or at either or both of the side-edges of said 25 glass-panes, whereby the insertion of said glass-panes and the removal thereof are facilitated from either top, bottom or side edges thereof as occasion may require.

Another object of the invention is to provide a lock-seam in the metal at the bottom of each of the said grooves that form the receptacles for the edges of the glass-panes, such lock-seams greatly strengthening the joints and materially saving in labor in the 35 making of such joints in the bottom of said grooves, and, also, making it possible to construct each of the side-stiles and top and bottom rails of one piece of metal and placing the joint or seam in the most remote 40 point away from the effects of fire and weather.

Other features of the invention will be fully hereinafter described and particularly pointed out in the claim.

45 In the accompanying sheet of drawings, illustrating my invention herein, Figure 1 is an elevation of the inner face of my metallic window-sash; Fig. 2, a horizontal, sectional plan taken on the dotted-line *a*, *a*, of Fig. 1; Fig. 3, a vertical, sectional elevation taken on the dotted-line *b*, *b*, of Fig. 1; Fig. 4, a side elevation of Fig. 1; and Fig. 5, a fragmentary section (on a somewhat larger scale) of the top rail or bar, showing

the groove reducer or partial filler for the glass-pane and, also, showing the lock-seam feature at the bottom of said groove.

In these views, 1 indicates each of the vertical or side stiles of the hollow frame of the sash, 2 the top rail or bar thereof 60 and 3 the bottom rail or bar thereof.

4 indicates the customary deep flange projecting from one edge of each of the said side-stiles and 5 a similar flange projecting from the other edge of the said side-stiles, 65 but of lesser depth than the flange 4, and 4^a is a flange projecting from the outer edge of the bottom-rail 3, as customary. These flanges form the usual weather-guards and guide on the side and bottom 70 edges of the sash.

6 indicates each of the perpendicular grooves made in the sheet-metal along the inner edges of the side-stiles 1, lock-seams 75 7 being made in the bottoms of said grooves 6, in the most hidden and protected part of the side-stiles, as seen in Fig. 2. Said side-grooves 6 are both of equal depth.

8 indicates a hollow perpendicular center-bar made of sheet-metal and rigidly secured in place on the weather side of the 80 sash.

9 indicates a hollow perpendicular center-bar corresponding to and registering with said center-bar 8 but arranged on the inner 85 face of the sash and detachably-secured in place by means of screws 10 whose threaded shanks engage transverse anchors or clips 11 provided within the hollow of said center-bar 8, as best seen in Fig. 2, bars 8 and 9 90 forming a two-part munition for a sash having a multiple of lights or sheets of glass. Perpendicular seats or grooves 12 are provided between said center bars 8 and 9 for the reception of the inner vertical edges of 95 the glass-panes 13, that are removably-held within the sash by means of the detachable center-bar 9. It is necessary to have the bar 9 detachable in order to insert the lights 13 into place in the upper and lower rails 100 and the side-stiles of the sash, as seen in Figs. 1 and 2.

14 indicates a groove constructed in the sheet-metal of the top-rail 2 along its inner or bottom edge, and 15 is a groove similar 105 in depth and character to that of groove 14 but made along the top edge of the bottom-rail 3 of the sash.

A lock-seam 16 is provided in the bottom of each of the grooves 14 and 15 and constructed in the same manner as the lock-seams 7 made in the bottoms of the side-grooves 6.

17 indicates a transverse bar made of metal or other suitable non-combustible material and inserted in either or both of the grooves 14 and 15, with its opposite ends passing through suitable openings or orifices pierced in the side-stiles 1 of the sash-frame. Bar 17 acts as a supporting-filler to somewhat reduce the depth of the groove when the glass-pane has been inserted into place, the upper edge of such glass-pane being first inserted in the upper groove 14 the full depth of the latter so that the lower edge of the glass-pane may pass the upper edge of the pane-opening in the bottom-rail 3, but the upper filling-bar 17 must not be in place in said groove 14 when the pane is initially inserted, such filler-bars 17 being inserted after the pane has been duly inserted with both its upper and lower edges resting in the grooves 14 and 15, respectively. Said filler-bars 17 are readily slid into place in the bottoms of the several grooves 14 and 15, as the glass-pane drops into the bottom of groove 15 on initial insertion, at which time the upper filler-bar can be slid into position and then the pane can be raised so that its upper edge contacts with the lower edge of the upper filler-bar and then the lower filler-bar can be readily inserted.

A number of screws 18 are inserted from both front and back of the window-sash so that their inner ends engage threaded holes made in the filler-bars 17. These screws 40 strengthen the structure, especially at the several corners thereof and in the long intervals between said corners both transversely and vertically of the sash. These serve to prevent warping of the plates and 45 the filler-bars act as reinforces to very materially strengthen and stiffen the hollow structure of the sash-frame. These are important features of the invention herein, the filler-bars and their screws making the hollow 50 frame of the sash more rigid and less liable to warp. Said filler-bars can be used in the side-grooves 6, the same as in the top and bottom grooves 14 and 15, respectively, the use of them in said side-grooves enabling

the ready insertion of the glass from its side edges. 55

In a swinging sash, it is important to have the filler-bar present in the bottom of the upper groove 14, so that the glass-pane cannot slide upward after once being placed in the sash. Under ordinary circumstances, a filler-bar would not be necessary in the said upper groove 14, as the filler-bar in the lower groove 15 would be ample to support the glass-pane in proper relation after initial 65 insertion.

Longitudinal hook-formations 19 and 20 are made along the face of the top-rail 2, as best seen in Fig. 5, for the customary purpose of engaging like hook-formations 70 disposed upwardly on the lower meeting-rail of the upper sash, the sash shown in Fig. 5 being the lower one. These hook-formations are of several depths in construction and are adapted to the purpose of 75 drawing the two meeting-rails together when the sashes are closed and forming a double bulwark against fire and weather.

I claim:

A metallic window-sash having hollow walls and comprising vertical side-stiles, horizontal top and bottom rails, a vertical hollow munition made of sheet metal and having its vertical inner bar removable, guideways lying between the rigid and removable bars of said munition, inwardly-facing recesses or grooves made along said side-stiles and said top and bottom rails, lock-seams in the bottoms of each of said grooves in the side-stiles and top and bottom rails, 90 a removable reducer and reinforcing filler-bar of constant width and thickness and fitting within but of lesser depth and of greater length than the respective depths and lengths of either of said grooves in the 95 said horizontal top and bottom rails, transverse screws for securing said reinforcing filler-bars in the hollow frame walls and glass lights or panes suitably inserted and fitting within all said grooves in the sash 100 and duly contacting along their upper and lower edges and full horizontal length with said reinforcing filler-bars.

EDWIN R. PROBERT.

Witnesses:

JOHN ELIAS JONES,
NORMA KEISER.
